(57) **CLAIM**

The ornamental design for a tent, as shown and described.

DESCRIPTION

FIG. 1 is a front perspective view of a tent showing a first embodiment of our new design;

FIG. 2 is a front view thereof;

FIG. 3 is a rear view thereof;

FIG. 4 is a right side view thereof, the left side view being a mirror image of the right side view;

FIG. 5 is a top view thereof; and

FIG. 6 is a bottom view thereof, where the bottom surface of the tent is unclaimed subject matter.

FIG. 7 is a front perspective view of a tent showing a second embodiment of our new design;

FIG. 8 is a front view thereof;

FIG. 9 is a rear view thereof;

FIG. 10 is a right side view thereof, the left side view being a mirror image of the right side view;

FIG. 11 is a top view thereof; and,

FIG. 12 is a bottom view thereof, where the bottom surface of the tent is unclaimed subject matter.

The features shown in broken lines depict environmental or other associated subject matter and form no part of the claimed design.

1 Claim, 12 Drawing Sheets
